DOOR CLOSER

Raymond K. Gray, Skokie, and Stanley C. Wohniak, Chicago, Ill., assignors to The Illinois Lock Company, a corporation of Illinois

Filed Sept. 30, 1958, Ser. No. 764,400

7 Claims. (Cl. 16—52)

This invention relates to an hydraulic piston and cylinder door closer.

Many previously known piston and cylinder door closing or checking devices utilizing hydraulic damping fluid are so constructed that a certain amount of air is trapped with the fluid in front of the piston, causing an objectionable bounce at the start of the closing operation of the door. Solutions have been proposed for this problem, but they are generally unsatisfactory commercially, as they involve either complicated fluid passageway arrangements or complicated mechanical linkages which permit mounting the cylinder in a vertical rather than a horizontal position. As a result, such devices are too expensive to be commercially practicable.

It is a principal object of the present invention to provide a novel, yet simple, piston and fluid passageway arrangement for an hydraulic door closer, which reduces the air bounce problem.

Another object of the invention is the provision of a novel arrangement for varying the terminal closing force of the device.

One feature of the invention is the provision of an hydraulic piston and cylinder door closer including a fluid passageway through the piston for flow of fluid on movement of the piston during opening of the door, the passageway having an inlet spaced from the piston proper. Another feature is that the inlet of the fluid passageway is a port formed in the lower surface of a boss extending from the piston, and spaced from the piston face.

A further feature is that the fluid passage inlet port means is elongated in a dimension along the axis of the cylinder, so that the fluid is drawn into the passage over a substantial area.

Still another feature is that the piston is provided with a fluid return passageway having a flow restricting orifice therein, a pin is associated with the flow restricting orifice, and operable therein to change the rate of flow of fluid through the orifice at the termination of the closing movement of the door, together with means for adjusting or varying the point of operation of the pin. Yet a further feature is that the pin is movably mounted on the piston, extending through the flow restricting orifice, and has portions of differing cross-section, the pin engaging the end of the cylinder and moving relative to the orifice to change the cross-section of the portion in the orifice during the terminal portion of the piston movement.

Another feature is that the piston is provided with a fluid return passageway having an exposed flow restricting orifice therein, a pin is mounted in the cylinder and projects into the flow restricting orifice as the piston nears its terminal position, and means are provided for varying the relative positions of the piston and the pin, to provide differing terminal closing rates. Yet a further feature is that the stop position of the piston is varied by changing the point of connection of the piston rod to the door.

And another feature is that the check valve in the fluid flow passage through the piston includes a surface having a plurality of orifices therein carried in a recess in the face of the piston, with the orifices forming a portion of the flow passage, an annular member mounted in the recess and having a valve restraining portion, and the valve member carried between the surface and the annular member, for covering a portion of the orifices.

A further feature is that the bracket member for secur-

2

ing the piston rod to the door has mounting holes therein which are offset or unequally spaced from the point at which the piston rod is connected with the bracket, so that the bracket may be placed in one position with the piston closed for marking the point of attachment to the door, and then secured to the door in reversed position, to apply a preload to the return spring of the closer.

Yet another feature is that the closer includes a bracket secured to the door frame and a pin for securing the closer to the bracket, including means for preventing rotation of the pin relative to the bracket.

Further features and advantages will readily be apparent from the following specification and from the drawings, in which:

FIG. 1 is a horizontal section taken through a door and frame, illustrating the mounting of the door closer;

FIG. 2 is a longitudinal section taken through the door closer;

FIG. 3 is an enlarged fragmentary section through the piston and a portion of the cylinder, in one position;

FIG. 4 is an enlarged fragmentary section through the piston and a portion of the cylinder, in another position;

FIG. 5 is an enlarged fragmentary section through the piston and a portion of the cylinder in a third position;

FIG. 6 is a fragmentary plan and sectional view illustrating one step in securing the piston rod bracket to the door;

FIG. 7 is a view similar to FIG. 6 with the bracket secured to the door and the rod attached to the bracket;

FIG. 8 is a view taken generally along line 8—8 of FIG. 3;

FIG. 9 is a bottom view of a modified piston;

FIG. 10 is a sketch illustrating the flow of hydraulic fluid with the novel fluid passageway inlet port arrangement of this invention;

FIG. 11 is an enlarged fragmentary section through the piston and portion of the cylinder, similar to FIG. 3, illustrating a modified form of the invention;

FIG. 12 is a view similar to FIG. 11 showing the parts in another position;

FIG. 13 is a view similar to FIG. 11 showing a further modified form of the invention; and

FIG. 14 is an enlarged sectional view through the frame bracket and connecting pin.

Door closers for general purpose home use, as for screen and storm doors, are usually air buffered piston and cylinder devices. These closers normally have a relatively short life, as of the order of six to eight years. A few types of hydraulic closers, both piston and cylinder, and rotary vane constructions, have been marketed for home use. These closers are generally subject either to the air bounce problem discussed above, or are relatively expensive. The hydraulic piston and cylinder closer disclosed and claimed herein not only eliminates the air bounce problem, but is of rugged yet relatively inexpensive construction, having a long life while well within the price range for home use.

Referring now to the drawings and particularly to FIG. 1, a storm door 15 is mounted by hinge 16 on a frame 17. Closing movement of the door is limited by stop 18 secured to the jamb portion 19 of frame 17. A closer, indicated generally as 20, includes a cylinder 21 secured to frame bracket 22 attached to the door frame adjacent the hinged edge of the door. A piston rod 23 extends from the opposite end of cylinder 21 and is secured to door bracket 24 attached to an intermediate point of the door 15.

In FIG. 2 it is seen that the cylinder 21 is provided with two end members 26 and 27. End member 26 has an ear 28 projecting therefrom with a hole 29 formed in the end to receive a pin connecting the cylinder with door frame bracket 22. Piston rod 23, which extends through

a bore 30 provided in end member 27, is affixed at its inner end to piston 32, slidably carried within the cylinder 21. The piston 32 and rod 23 are urged toward the position shown in FIG. 2 by return spring 33 which has one end bearing against the face 34 of the piston, and the other end on cup washer 35, which in turn is seated on end member 27 and serves as a retainer for sealing ring 36. A relatively heavy buffer spring 37 is located inside return spring 33 and is centered by a conical portion 35a of cup washer 35. A sleeve 37a, preferably of a plastic material as nylon, surrounds piston rod 23 inside the buffer spring, to prevent the spring from scarring the piston rod.

As best seen in FIG. 3, piston 32 has an elongated boss or extension portion 40 extending from the face 34, to which piston rod is secured, by pin 41. A fluid passage through the piston includes bore 42 which extends longitudinally through boss 40 and communicates through recess 43, formed in the face 44 of piston, with the space 45 to the left of the piston as viewed in the drawings. Bore 42 communicates with space 46, to the right of the piston, through a plurality of ports 47, 48 and 49 formed in the enlarged lower portion of boss 40 which is thicker than the top portion so that the lower surface of the boss is closely adjacent the cylinder wall. Carried in the recess 43 is a check valve arrangement including valve seat plate 52, provided with a plurality of peripherally located apertures 53 (FIG. 8) and a centrally located aperture 54. Overlying plate 52 is an annular valve retainer 55, having an L-shaped cross-section with an inturned flange 55a. Carried between flange 55a and valve seat plate 52 is check valve 56 which has a centrally located orifice 57 that is several times the size of orifice 54 in plate 52. A portion 58 of the piston 32 is formed over the top of annular valve retainer 55 as by a rolling operation, holding the entire valve assembly in recess 43.

Cylinder 21 is filled with a fluid having a high viscosity index, as an hydraulic damping fluid. The quantity of fluid placed in the cylinder is such that the level is about $\frac{1}{8}$ to $\frac{3}{16}$ of an inch below the top of the cylinder 21 with the parts in the fully closed position, as shown in FIG. 2.

When the door is opened, the piston 32 is retracted, compressing return spring 33. The movement of the piston away from end member 26 creates a vacuum or reduced pressure in the space 45 to the left of the piston, drawing the hydraulic fluid from the space 46 through the piston. The flow of fluid during this movement is through ports 47, 48 and 49, bore 42, apertures 53 and 54 in plate 52, and the central aperture 57 of valve 56, which is unseated. If the opening movement of the door is continued, buffer spring 37 will also be compressed.

When the door is released, the return spring, or springs if both are compressed, urge the piston to the left, tending to close the door. This action moves valve member 56 to the right, causing it to seat on plate 52 closing orifices 53, so that the return flow of fluid must pass through flow restricting orifice 54. The size of this orifice, as related to the viscosity of the hydraulic fluid and the pressure of the return spring, governs the closing speed of the device.

In the embodiment of FIGURE 3, as piston 32 nears its terminal position, adjacent end member 26, the point 60 of a pin 61 mounted in the end member, enters speed control orifice 54, restricting the rate of flow therethrough, and slowing the closing action of the door. The outer portion 61a of pin 61 has a smaller diameter than the base portion 61b, so that the closing movement of the door is slowed in two stages. This is illustrated in FIGS. 4 and 5, which show the portions 61a and 61b, respectively, of the pin extending into flow controlling orifice 54. In one embodiment of the device where the flow restricting orifice 54 has a diameter of 0.050 inch, the portion 61a of the flow restricting pin has a diameter of 0.034 inch, and the portion 61b has a diameter of 0.040 inch. The opening 57 in the valve member is sufficiently

large so that the flow through it is not affected by the member 61.

The location of ports 47, 48 and 49 which open at the bottom of piston extension 40 reduces the possibility of air being drawn through the piston into the space 45 when the door is opened. Furthermore, the spacing of the ports along the length of piston extension 40, with the largest opening the farthest away from the face 34 of the piston, provides an elongated port means which causes the fluid to flow into the piston in a uniform manner. In FIG. 10, the action of the surface of the hydraulic fluid with the port arrangement of FIG. 3 is illustrated at 64, showing how the fluid is drawn through each of the spaced ports. Where only a single port is provided in the face of piston 34, the surface of the hydraulic fluid follows the broken line 65, and air is often drawn through the piston, resulting in the objectionable "bounce" operation discussed above.

FIG. 9 is a bottom view of a modified piston with a single wedge shaped intake port 67 located in the bottom or lower surface of piston extension 40, with the opening tapering downwardly as it approaches the face 34 of the piston.

Preferably the cross sectional area of the ports is equal to the area of bore 42, for efficient fluid flow.

The needle valve or pin 61, which provides slowing of the door at the end of the closing operation, may be utilized to provide a terminal speed control. In FIG. 7, it will be seen that the door bracket 24 is provided with three sets of holes 68, 69 and 70, to one of which piston rod 23 is secured by pin 71. With piston rod 23 connected in holes 68, the piston closes fully, almost to the surface of end member 26, with full slowing of the operation. If piston rod 23 is connected with holes 69, the terminal position of the piston is as shown in FIG. 4, with only partial slowing action as pin 61 is in orifice 54 for a shorter portion of the movement. If the piston rod is secured in holes 70 of the door bracket, the terminal position of the piston is as illustrated in FIG. 3, with the flow restricting orifice 54 stopped short of the end 61a of needle valve 61. With this arrangement of the closer, the door is moved at a constant speed and there is no slowing as it latches. The differing cross-sections of portions 61a and 61b of the pin enhance this control, as the closing speed is slower in the final portion of the movement (using bracket holes 68) due to the further reduction in flow area through the orifice.

The above described arrangement permits adjustment of the closer to accommodate different types of doors, latches and operating conditions.

The mounting holes 72 and 73 for door bracket 24 are offset from the connecting pin holes 68, 69 and 70, with holes 68 being spaced farther from mounting hole 73 than the distance between holes 70 and mounting hole 72. This arrangement facilitates the installation of the closer with the necessary amount of pre-load on return spring 33. As shown in FIG. 6, door bracket 24 is initially connected with piston rod 23 by pin 71 through holes 70, with mounting hole 72 toward the left or hinge edge of the door. The return spring 33 is fully extended, with the face 44 of piston 32 engaging end member 26. The positions of holes 72 and 73 are marked on door 15, as by a pencil 74. Door bracket 24 is removed from piston rod 23, inverted and attached to the door with hole 73 to the left and hole 72 to the right. Piston rod 23 is then reconnected with door bracket 24, by pin 71 in holes 68. As these holes are spaced farther from mounting hole 73 than the distance between hole 70 and mounting hole 72, piston 32 is moved away from the face of end member 26, as shown in FIG. 2, applying a pre-load to closing spring 33.

Cylinder end 27 through which piston rod 23 extends, has mounted in bore 30 a bearing sleeve 75, preferably of a low friction material, as nylon. Mounted in an enlarged portion 30a of the bore at the outer end of end

member 27 is an annular rod seal 76 of flexible sealing material backed up by supporting washer 77. A leather rod wiper 78 is located outside supporting washer 77, and held in place by a retaining washer 79. The parts 77, 78 and 79 are of any suitable construction and may be conventional. The provision of an elongated bearing surface 75 at the inner face of end member 27, with the sealing element at the outer face thereof, eliminates undue wear on the sealing element due to misalignment of the piston rod during operation.

In the modification of FIGS. 11 and 12, parts corresponding with parts illustrated and identified in preceding figures are designated by the same reference numerals. A pin 71' is carried in the bore 42 of piston 32 and is urged outwardly thereof through flow controlling orifice 54 by a spring 71", which has an end portion 71a" tightly coiled about pin 71' and engaging a shoulder 71a' formed thereon, supporting the pin. The portion 71b' of the pin, which is normally within orifice 54 whenever the piston is spaced a substantial distance from cylinder end member 26, reduces the flow of hydraulic fluid through the orifice to such a degree that the door closes slowly. As the piston nears end member 26, the sharpened point 71c' of the pin engages a plug 72' carried by end member 26, and the movement of the pin is stopped. As piston 32 continues to move toward the left, the reduced portion 71d' of the pin enters flow controlling orifice 54, and the final closing movement of the door is accelerated. This insures that the door will latch securely, even with a latch that is hard to operate.

The end surface of plug 72' which is engaged by the pointed end 71c' of the pin is provided with a conical depression 72a', so that the pin is properly aligned during the relative movement between it and piston 32.

Plug 72' has a threaded portion 72b' received in a nut 73' secured in the portion 26a of cylinder end member 26. A knurled knob 72c' is manually engageable to permit adjustment of the position of plug 72' relative to cylinder end member 26, and thus to control the point at which the closing rate of the door is changed. An O-ring 74' seals the joint between plug 72' and end member 26, and is held in position by a retainer washer 75'.

In FIGURE 13, a modified control pin 78' is shown carried by spring 71" having a portion of reduced cross-sectional area 78a', which is normally positioned within flow controlling orifice 54, and a portion of enlarged cross-sectional area 78b' which is moved into the flow controlling orifice 54 during the terminal closing movement of the door. This slows the movement of the door as it latches.

Referring now to FIGURE 14, it will be seen that the frame bracket 22 includes two spaced portions 22a and 22b between which is received the end portion of ear 28. A pin 80 is inserted through aligned openings in bracket portions 22a and 22b, and through opening 29 in ear 28. The pin 80 is provided with a portion 81 which engages with bracket portion 22a, preventing pin 80 from rotating during operation of the closer. For example, the shoulder portion 81 of pin 80 may be knurled and of such a diameter that it has a driven engagement with the bracket. All relative motion between the closer and the bracket occurs along the surface of hole 29 and the body of pin 80, and there is no wear on the relatively small surfaces of engagement between the pin and the bracket.

While we have shown and described certain embodiments of our invention, it is understood that it is capable of many modifications. Changes, therefore, in the construction and arrangement may be made without departing from the spirit and scope of the invention as disclosed in the appended claims.

We claim:

1. In a hydraulic door closer: a cylinder adapted to contain hydraulic fluid; a piston slidable in said cylinder;

a spring urging said piston toward one end of said cylinder; means for connecting said piston and cylinder to a door and an associated frame, opening movement of said door moving said piston toward the other end of said cylinder and thereby compressing said spring; a boss having a lower wall extending outwardly from said piston, and having a bore; and means defining a fluid passage through said piston for flow of hydraulic fluid on movement of the piston toward said other end of the cylinder, said passage including said bore and port means through the wall of said boss, horizontally spaced a substantial distance from the face of said piston, said port means opening through the lower wall of said boss and having a greater extent in a direction along the axis of the cylinder than in a direction transverse thereto.

2. A hydraulic piston and cylinder device of claim 1, wherein said port means comprises a series of openings of graduated size extending longitudinally along said boss, with the largest opening spaced the farthest from the face of said piston.

3. A hydraulic piston and cylinder device of claim 1, wherein said port means is a wedge-shaped opening having its base portion spaced farthest from the face of said piston and tapering toward the piston face.

4. In a hydraulic door closer; a cylinder adapted to contain hydraulic fluid; a piston slidable in said cylinder; a spring urging said piston toward one end of said cylinder; means for connecting said piston and cylinder to a door and an associated frame, opening movement of said

30 door moving said piston toward the other end of said cylinder and thereby compressing said spring; a boss extending outwardly from said piston, and having a bore; and means defining the principal fluid passage through said piston for flow of hydraulic fluid on movement of

35 the piston toward said other end of the cylinder, said passageway including said bore and port means through the wall of said boss, spaced a substantial distance from the face of said piston, the cross section of said port means being substantially equal to the cross section of said bore.

5. In a hydraulic door closer: a cylinder adapted to contain hydraulic fluid; a piston and rod slidable in said cylinder; a spring urging said piston toward one end of said cylinder; means, including a bracket, for connecting said piston rod and cylinder to a door and an associated frame, opening movement of said door moving said piston toward the other end of said cylinder and thereby compressing said spring; means defining a fluid passage through said piston for flow of hydraulic fluid on movement of the piston toward a stop position at said one end of the cylinder, said fluid passage including an exposed flow restricting orifice; a stepped pin having portions of differing cross-section mounted in said cylinder and projecting into said flow restricting orifice as said piston

50 nears stop position, said bracket connecting said piston rod to said door having a plurality of spaced connection points selectively receiving said piston rod for adjusting the stepped portions of said pin with respect to said orifice.

6. In a hydraulic door closer: a cylinder adapted to contain hydraulic fluid; a piston slidable in said cylinder; a spring urging said piston toward one end of said cylinder; means for connecting said piston and cylinder to a door and an associated frame, opening movement of said

65 door moving said piston toward the other end of said cylinder and thereby compressing said spring; a boss having a lower wall extending outwardly from said piston and having a bore therethrough; and means defining a fluid passage through said piston for flow of hydraulic fluid on movement of the piston toward said other end of the cylinder, said passage including said bore and port means through only the lower wall of the boss, said port means being spaced from the face of said piston a distance greater than the distance between the port means

and the bottom of the cylinder, and the bottom surface of the lower wall of the boss being closer to the bottom of the cylinder than the top surface of the boss is to the top surface of the cylinder.

7. In a hydraulic door closer: a cylinder adapted to 5 contain hydraulic fluid; a piston slidable in said cylinder; a spring urging said piston toward one end of said cylinder; means for connecting said piston and cylinder to a door and associated frame, opening movement of said door moving said piston toward the other end of said cylinder and thereby compressing said spring; means defining a fluid passage through said piston for flow of hydraulic fluid on movement of the piston toward a stop position at said one end of the cylinder, said fluid passage including a flow restricting orifice; and a pin associated 10 with the flow restricting orifice in said fluid passage and operable to vary gradually the rate of flow at the termination of piston movement toward said stop position, the relative position of said piston and pin being adjustable for selectively varying the rate of flow of the 15 hydraulic fluid, by changing the point of connection of the closer to said door.
